UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

ADJUSTABLE DRIVING-BOX.

1,399,809.

Specification of Letters Patent.

Patented Dec. 13, 1921.

Application filed June 27, 1921. Serial No. 480,778.

To all whom it may concern:

Be it known that I, WILLIAM M. SHEEHAN, a citizen of the United States, residing at St. Louis, Missouri, have invented a certain new and useful Improvement in Adjustable Driving-Boxes, of which the following is a full, clear, and exact description, such as will enable others skilled in the art to which it appertains to make and use the same, reference being had to the accompanying drawings, forming part of this specification.

My invention relates to journal boxes for railway locomotives, and consists in improvements upon the construction shown in Patent No. 1,377,557, issued to Ray M. Brown, May 10, 1921.

The main object of my invention is to provide means for adjusting the axle journal box transversely of the locomotive pedestals in order to secure a proper fit when a box, pedestal, and wheel are assembled, and also to take up wear at any subsequent time.

In the accompanying drawings, which illustrate a selected embodiment of my invention,—

Figure 1 is a longitudinal vertical section through a locomotive pedestal, showing the journal box, axle and wheel and equipped with my invention.

Fig. 2 is a transverse vertical section on line 2—2 of Fig. 1.

Fig. 3 is a transverse horizontal section through the box on line 3—3 of Fig. 1.

The locomotive driving wheel 1 is mounted upon the axle 2 which carries the journal box 3 in the usual manner. Journal box 3 is mounted in a pedestal 4 which is provided with the pedestal binder 5.

As shown in the above-mentioned Brown patent, journal box 3 is flangeless, and, so far as the pedestal is concerned, is free to move transversely thereof toward and from wheel 1 or longitudinally of the axle and the journal receiving recess in box 3.

By reference to Fig. 2, it will be seen that the outer face of journal box 3 bears against the inner face of the hub of wheel 1.

Pedestal 4 is provided with a bracket 6 which extends inwardly and has a pad 7 facing axle 2 but spaced therefrom a greater distance than the side of box 3. A container member 8 is bolted to pad 7 and is provided with a vertical recess 9 in which a journal

box shoe 10 is slidably mounted. Between 55 shoe 10 and the rear of recess 9 is a wedge 11 which forms a bearing for shoe 10. The contacting faces of shoe 10 and wedge 11 are inclined from the vertical and a bolt 12 passes through wedge 11 in the plane of the 60 inclination of the shoe contacting face, engaging the top of the wedge, and its lower end passes through a rib 13 on member 8, and, by means of nuts 14, may be drawn downward to lower wedge 11 and thereby 65 feed shoe 10 and box 3 outwardly. Member 8 is provided with an integral flange 15 in which is screwed a set screw 16 which may be used for locking shoe 10 in any desired position.

When the parts shown are assembled, bolt 12 is tightened until the proper fit between journal box 3, shoe 10, and wheel 2 is obtained, and the bolt and shoe are then locked in position. At any time when the play between the box and the wheel becomes excessive, nuts 14 and set screw 16 may be loosened, wedge 11 inserted a sufficient distance to take up the play, and bolts 14 and set screw 16 again tightened.

If it is desired to remove box 3 for the purposes of repair, container member 8 with shoe 10 and wedge 11 may be entirely removed, journal box 3 moved inwardly from the pedestal and rotated on axle 2 and dropped therefrom. As pointed out in the above-mentioned patent, this eliminates the necessity of disconnecting the driving rods and dropping the wheels and axle into pits, or similar expensive operations.

I contemplate the usual modifications in my invention, without departing from the spirit thereof, as set forth in the following claims:

I claim:

1. In combination with a locomotive pedestal, an axle journal box, and means for adjusting the movement of said box transversely of the pedestal.

2. In combination with a locomotive pedestal, an axle journal box, and means adjustable on and removable from the pedestal for limiting the movement of said box transversely of the pedestal.

3. In combination with the pedestal and wheel of a locomotive, an axle journal box movable transversely of the pedestal and held against movement toward the wheel by

- engagement of the hub of the wheel and against opposite movement by an adjustable bearing shoe.
4. In a locomotive, a pedestal, a journal box therein, an integral side extension on said pedestal, a containing member removably secured to said side extension, and journal box holding means mounted in said member and adjustable transversely of said pedestal.
5. In a locomotive, a wheel, an axle therefor, a pedestal, an axle journal box movable transversely of said pedestal, a container member removably secured to said pedestal, a shoe slidably mounted in said member and adapted to limit transverse movement of said journal box, and a wedge between said shoe and a surface of said member for adjusting said shoe to coöperate with said wheel for holding said journal box in a predetermined position.
6. In a locomotive pedestal, a transversely extending bracket, a container member removably secured thereto, a longitudinal recess in said member, a tapered wedge seated in said recess, a journal box bearing shoe seated against said wedge, and means for inserting said wedge between its seat and said shoe.
7. In a locomotive pedestal, a transversely extending bracket, a container member removably secured thereto, a longitudinal recess in said member, a tapered wedge seated in said recess, a journal box bearing shoe seated against said wedge, a bolt passing through said wedge in the plane of its taper, elements coöperating with said bolt and member to draw said wedge through said recess, and means for locking said shoe in wedge-adjusted position.
8. The combination with a locomotive frame provided with journal box openings, of flangeless journal boxes positioned in said openings, the outer projecting ends of which journal boxes are positioned adjacent to the hubs of the wheels carried by the axle that has bearing in said journal boxes, and detachable brackets disposed toward each other and secured to a part of the locomotive frame on opposite sides of the axle space and provided with relatively movable means for adjustably retaining the journal boxes in position within said journal box openings.
9. The combination with a locomotive frame provided with journal box openings, of flangeless journal boxes positioned in said openings, the outer projecting ends of which journal boxes are located adjacent to the hubs of the wheels carried by the axle that has bearing in said journal boxes, detachable brackets disposed toward each other and secured to a part of the locomotive frame on opposite sides of the axle space, and removable bearing plates detachably and adjustably secured to said brackets and coöperating with the inner faces of the journal boxes to retain them in position.
10. In combination with a locomotive pedestal, an axle journal box, a recess therein, adapted to receive an axle journal, and means for adjusting the journal box longitudinally of the axis of the recess.

In testimony whereof I hereunto affix my signature this 18th day of June, 1921.

WILLIAM M. SHEEHAN.
